UNITED STATES PATENT OFFICE.

JOHN McTAMMANY, OF WORCESTER, MASSACHUSETTS.

MUSICAL INSTRUMENT.

No. 839,183.

Specification of Letters Patent.

Patented Dec. 25, 1906.

Application filed November 18, 1898. Serial No. 696,756.

To all whom it may concern:

Be it known that I, JOHN McTAMMANY, of Worcester, in the county of Worcester and State of Massachusetts, have invented certain new and useful Improvements in Musical Instruments, of which the following is a specification.

This invention has relation to automatic musical instruments of the class wherein the tone-producers are controlled by a selector through the medium of any suitable actuating devices, and more particularly to that class of instruments wherein two or more different kinds of tone-producers are utilized for producing harmonious musical effects.

The invention has for its object to provide an improved musical instrument of the class named whereby a greater variety of tone-producers can be used, finer effects can be produced, and musical compositions of a higher grade of excellence can be performed than heretofore.

It consists of an instrument possessing certain features of construction and arrangement of parts, all as illustrated upon the drawings, and now to be described in detail, and finally pointed out in the claims hereunto appended.

Reference is to be had to the accompanying drawings, and to the letters marked thereon, forming a part of this specification, the same letters designating the same parts or features, as the case may be, wherever they occur.

Of the drawings, Figure 1 represents in front elevation a musical instrument embodying my invention. Fig. 2 represents a side elevation of the same and the lower portion of the instrument being shown in section for the purpose of illustrating the bellows. Fig. 3 represents a section through the upper portion of the instrument on the line 3-3 of Fig. 1 and shows the three sound-producers which I have elected to employ and their actuating mechanism. Fig. 4 represents a transverse horizontal section on line 4-4 of Fig. 3. Fig. 5 represents a horizontal section on line 5-5 of Fig. 3. This section is taken on two different planes through the channel-board. Fig. 6 represents a vertical section on the line 6-6 of Fig. 3 and illustrates the musical comb. Fig. 7 represents a vertical section on the line 7-7 of Fig. 3 and illustrates the mechanism for controlling the wind-instruments or flutes which are located in the upper part of the casing. Fig. 8 represents in detail and in

perspective view the two controllers for the said flutes.

The instrument which is illustrated upon the drawings and which I shall now proceed to describe is intended to produce, as nearly as possible, the musical effect of a harp, a violin, and a flute. Inasmuch, however, as the harp and violin are provided with strings, I employ in lieu of them a set of reeds arranged to produce a "string tone" and a comb having its tongues constructed and arranged to give forth sounds resembling those produced by the strings of a harp. This I have done, as the strings of stringed instruments are liable to stretch and break and require constant tuning to keep them in order, and as this instrument is designed to be employed either for the house or in connection with nickel-in-the-slot mechanism such stretching, breaking, and tuning of the strings would be a serious objection.

I have elected to show the invention in its simplest form, and accordingly the reeds, the comb, and the flutes are sounded in unison; but it will be understood that substantially the same mechanism and apparatus may be employed to preserve the individuality of each instrument in concerted compositions. Of course the selector would necessarily have to be arranged to cause the actuation of the instruments separately; but this would be the work of a mechanic and could be readily accomplished in view of the apparatus now to be explained.

In its general appearance the casing which incloses the instruments and their controllers and the pneumatic devices for operating the controllers consists of three parts of different sizes, (indicated at A, B, and C.) The lower portion A forms a stand for the box-shaped portion B, upon which rests the upper portion C. When viewed in side elevation, the three portions of the casing look like boxes piled one above the other and graduated from large to small. The lower section A of the casing incloses the suction-bellows *a* and the reservoirs *a'* connected therewith and the pedals *a²* *a³*, which actuate the bellows. The pedals are connected by straps *a³* with disks *a⁴*, attached to a transverse shaft *a⁵*, journaled in bearings in the end walls of the lower portion A of the casing, said straps being secured at their ends to the movable boards of the bellows. The reservoirs *a'* communicate with the rear wind-chest *b*, formed in the top of the lower section

A of the casing. There is another wind-chest b' , separated from that at b by a partition b^2 , which communicates with the interior of two pressure-bellows $c c$, located above the wind-chests $b b'$, the movable boards of said bellows $c c$ being connected by straps $c' c'$ with disks $c^2 c^2$, secured to the rock-shaft a^5 . Between the bellows $c c$ there is a reservoir c^3 , which communicates with the wind-chest b' , as shown in dotted lines in Fig. 1.

The bellows $a' a'$ operate to withdraw the air by suction from the wind-chest b , while the bellows $c c$ force air under pressure into the wind-chest b' for a purpose to be explained in detail.

A platform d is supported by end standards d' on the top of the wind-chest b' and covers the bellows $c c$ and the reservoirs c^3 , and it is upon this platform that the upper portions B 20 C of the casings rest. The frame B incloses the reeds, the pneumatic actuators therefor, while the frame C contains the controllers for the flute, and the pickers for the comb. There is formed in said frame B two separate compartments $e e'$, one above the other, and the latter e' (which is a wind-chest) communicating by a trunk e^2 with the suction wind-chest b . The partition e^3 between the compartments $e e'$ is relatively thick, being formed, as shown, in three layers, and through said partition extend a plurality of apertures or ducts e^4 , arranged as shown in dotted lines in Fig. 4, said ducts having relatively small ports $e^5 e^6$, the lower ports e^6 being normally closed by the valves e^7 , which are adapted, however, to close the ports e^5 when they are raised.

The platform d is in reality a channel-board having a series of parallel wind channels or ducts d^2 , which extend to the front edge thereof and are adapted to be normally closed by a selector f , as shown in Fig. 2. This selector may consist of an elongated strip or sheet of suitable material, such as paper or sheet metal, adapted to be unwound from a roll f' by a winding-roll f^2 , driven by means to be described. This selector is provided with apertures adapted to register with the channels d^2 intermittently to cause the production of tones by the sounding instruments. Each channel d^2 ends in a circular chamber or recess d^3 in the upper face of the channel-board, (see Fig. 5,) across which is stretched a diaphragm d^4 . Upon this diaphragm rests the lower end of the valve-spindle e^8 of one of the valves e^7 , and consequently there is a duct d^2 directly below each one of the ducts e^4 . Hence each time an aperture in the selector registers with the mouth of one of the ducts d^2 the diaphragm at the end of the duct is raised by atmospheric pressure and the valve e^7 is raised to open the port e^6 and close the port e^5 . Each duct e^4 communicates by a windway g with a pneumatic actuator g' , located in the compartment e . These "actuators" or "mo-

tors," as I may term them, are small bellows, and they are arranged in four rows, two in the front and two in the rear of the wind-chest e , so that whenever a duct d^2 is opened and the valve e^7 is raised air will be drawn from the corresponding pneumatic motor g' through a duct g . To the movable portion of each pneumatic actuator or motor is secured a finger g^2 , upon which rests a vertically-arranged tracker g^3 , passed through suitable guides $g^4 g^4$ through the upper wall of the compartment e into a small wind-chest h , which communicates by a trunk h' with the wind-chest b .

Upon the top of the wind-chest h and near the front edge thereof are arranged reeds h^2 , of which three banks are shown in Fig. 3. There is a valve or pallet h^3 for each reed, and it is connected with a lever h^4 , centrally fulcrumed in a depending lug h^5 and resting at its rear end upon one of the trackers g^3 . Hence when one of the ducts d^2 is opened and its corresponding pneumatic motor or actuator g' is operated the latter will lift a tracker g^3 and swinging a lever h^4 upon its fulcrum will withdraw the valve of one of the reeds and permit said reed to sound as long as the duct or channel d^2 is opened, and hence almost any musical composition or work can be produced by the reeds.

The selector which I have previously referred to as being wound upon a roll f^2 is moved automatically by a suitable wind-motor (indicated more or less conventionally at j) and connected by a trunk or tube j^2 with the tube e^2 , leading to the wind-chest B. Said motor rotates a crank-shaft j' , having thereupon a pulley j^2 , connected by a belt j^3 with a pulley j^4 upon a shaft j^5 , located just behind the roll f^2 . On the shaft j^5 is a pinion j^6 , intermeshing with and driving a gear-wheel j^7 on the winding-roll f^2 . I shall not describe the wind-motor, as it *per se* forms no part of the present invention, and any motor, whether pneumatic, electrical, or spring-actuated, may be employed in its stead.

Next referring to the top portion C of the casing and the parts therein contained, it will be seen that in the lower portion of the frame C is secured a musical comb k , having a series of tongues k' , and below each tongue is an actuator or picker consisting of a longitudinally-movable bar or strip k^2 , having a tongue-engaging tooth k^3 and a damper k^4 . In front of the combs is a toothed or fluted roll k^5 , which is driven by a belt k^6 , passing around a pulley k^7 , secured to a trunnion k^8 , projecting out from the roll and around a pulley k^9 on the crank-shaft j' . Each picker rests upon guides $m m'$ and is provided with a tooth k^{10} , upwardly extending and under the fluted or toothed roll k^5 . The front end of each picker rests upon a rod or tracker n , supported in guides $m^2 m^3$, one in and one above the wind-chest h . Each tracker n rests

upon the end of one of the levers h^4 and is pressed downwardly by a spring n' . When one of the levers h^4 is swung about its fulcrum and its rear end lifted, it raises one of the trackers n and lifts the picker thereon up into proximity to the roll k^5 , and the latter engaging the tooth k^{10} moves the picker forward and causes the tooth k^3 to impinge upon its immediately-adjacent tongue k' to cause the latter to sound. As soon as the tooth k^3 impinges upon the tongue to cause it to vibrate and the tracker n is dropped the picker is carried backward by a device to be described, and the damper k^4 engages the tongue. The flutes, of which there are two in number, as shown, although more or less may be used, are arranged above the comb and are indicated at $o o'$, one being directly above the other. The closed ends of the flutes project out of the casing C and are connected by tubes o^2 with the pressure wind-chest b' , so that when the holes in the flutes are opened the latter are caused to sound. I speak of these instruments as "flutes," but it will be understood that I may employ fifes, flagiolets, piccolos, clarionets, and other forms of wind instruments.

Each flute has a series of finger-holes $o^3 o^3$, which are normally closed by controllers or keys o^4 . Two flutes are so arranged that substantially half of the notes or tones are produced by one and the balance by the other. Each controller or key o^4 is on the lower end of a rod or wire o^5 , movable in guides $o^6 o^6$ and is adapted to be raised by an arm o^7 , extending out from a rock-shaft o^8 and ending under a collar o^9 on said wire.

The rock-shafts o^8 are arranged one above the other, there being two sets of them, one set for each flute. These rock-shafts have their ends journaled in the end walls of the casing C , and each is provided with a short arm o^9 , resting upon or connected to a tracker-rod o^{10} , movable in guides o^{11} , and having its lower end resting upon or connected to the horizontal arm p of the bell-crank lever p' , fulcrumed at p^2 and having its substantially vertical arm p^3 connected by a pin-and-slot connection with one of the pickers k^2 . The weight of the trackers and the bell-cranks resets the pickers k^2 .

I have employed the terms "horizontal" and "vertical" in describing the arms of the bell-cranks and various other parts of the instrument; but it will be understood that I use them merely to aid in the description of the particular instrument which is shown and that I do not intend to limit myself in any way by them, as the various elements in the combination and the various parts of the instrument may be arranged in any other way as desired.

As the flute tones in the instrument shown on the drawings are all above the middle register or middle C, only the pickers for the

tongues above that note are connected with the controllers for the flutes, (see Fig. 7;) but I may provide for a flute tone for each tone of the reeds or comb.

It is apparent at once, without further explanation, that when the selector is passing in front of the channel-board the flutes, the musical comb, and the reeds are all sounded in accordance with a preconceived plan or arrangement, all being controlled by pneumatic devices whose action is regulated by the selector. As shown, the instrument is operated through manual effort; but where it is designed to be employed in connection with a nuckle-in-the-slot device I contemplate the employment of some other form of motor for actuating the bellows.

It will be understood that the various improved features of my invention may be employed separately or in other combinations and that various changes in the construction and arrangement shown may be made without departing from the spirit and scope of my invention.

Having thus explained the nature of the invention and described a way of constructing and using the same, though without having attempted to set forth all of the forms in which it may be made or all of the modes of its use, I declare that what I claim is—

1. An automatic musical instrument comprising a plurality of musical tongues, a wind instrument sounded by a blast of air, a selector and means governed thereby for varying the tones of said instrument, and means independent of the selector for automatically causing the sounding of said tongues and said wind instrument.

2. An automatic musical instrument comprising a comb having musical tongues; pickers therefor, each picker being a single loosely-supported strip, a continuously-rotating toothed roll adapted to operate the pickers, and pneumatic actuators for automatically thrusting said pickers into engagement with said roll.

3. In combination, a comb having a plurality of musical tongues; a plurality of pickers, each consisting of a bar or strip having a tongue-engaging projection, and a tooth; a rotary toothed roll adapted to engage the tooth on each of the pickers; and automatic actuators for moving the pickers into engagement with the roll whereby their projections engage and vibrate the said tongues.

4. In combination, a comb having a plurality of musical tongues; a plurality of pickers, each consisting of a bar or strip having a tongue-engaging projection, and a tooth; a rotary toothed roll adapted to engage the tooth on each of the pickers; automatic actuators for moving the pickers into engagement with the roll whereby their projections engage and vibrate the said tongues, and means for returning said pickers to inoperative position.

5. In combination, a vertically-arranged comb having its tongue projecting downward, a plurality of pickers arranged below said comb in a plane intersecting that of the 5 tongues, whereby said pickers remain normally out of contact with the tongues, a rotary toothed roll above the pickers, and actuators for lifting the pickers into engagement

with the roll and the tongues whereby said roll causes said pickers to vibrate said tongues. 10

In testimony whereof I have affixed my signature in presence of two witnesses.

JOHN McTAMMANY.
